No. 854,444.

PATENTED MAY 21, 1907.

E. O. WARNER.

CAR COUPLING.

APPLICATION FILED NOV. 15, 1905.

UNITED STATES PATENT OFFICE.

EDWARD O. WARNER, OF HAVERFORD, PENNSYLVANIA, ASSIGNOR TO LATROBE STEEL AND COUPLER COMPANY, OF CAMDEN, NEW JERSEY, A CORPORATION OF NEW JERSEY.

CAR-COUPLING.

No. 854,444.

Specification of Letters Patent.

Patented May 21, 1907.

Application filed November 15, 1905. Serial No. 287,391.

To all whom it may concern:

Be it known that I, EDWARD O. WARNER, a citizen of the United States of America, residing in Haverford, in the county of Delaware, in the State of Pennsylvania, have invented a certain new and useful Improvement in Car-Couplers, of which the following is a true and exact description, reference being had to the accompanying drawings, which form a part thereof.

My invention relates to car couplers having the general characteristics of the master car builders type, and has for its object to provide a new and efficient mechanism for opening the jaw of the coupler by means of the lifting of the locking pin.

The nature of my improvements will be best understood as described in connection with the drawings in which they are illustrated and in which

Figure 1, is a plan view of a coupler provided with my improvements and shown on the horizontal section 1—1 of Fig. 2. Fig. 2, is a vertical section on the line 2—2 of Fig. 1. Fig. 3, a view similar to Fig. 2, but showing the knuckle opening device in operation. Fig. 4, is a cross sectional view on the line 4—4 of Fig. 2, looking toward the left. Fig. 5, is a perspective view of the knuckle, showing also the knuckle opening lever and the lug on the locking pin through which the lever is operated, and Figs. 6 and 7, are perspective views illustrating modifications of a detailed construction.

A, is the usual hollow draw bar of the coupler, A', the head in which is formed the vertical locking pin hole A², the hole being somewhat contracted as it passes through the metal forming the lower side of the head, where a shoulder A³, is provided, serving both as a rest for the main locking section of the pin and also as a rest for the lock set shoulder on the extension of the pin.

B, is the knuckle pivoted to the head in the usual way, and having a tail B', lying within the head and formed with an extension B², the upper side B³, of which forms a rest for the locking pin when the jaw is opened, while the under side B⁴, is given an inclined or cammed form to assist in the opening of the knuckle.

C, C', are sections of the locking pin, the part C', being the main locking portion of the

pin, formed with a bottom shoulder C², which is adapted to rest either on the ledge A³, of the head or on the supporting surface B³, of the knuckle tail. Extending down from one side of the section C', is the pin prolongation C³, which is formed with a lock set lug C⁴, adapted to rest on the ledge A³, when the pin is lifted and also with a lug C⁵, which is preferably given the cam or hook form best shown in Fig. 5, and which extends beneath the knuckle opening lever to be described.

D, is a pivot formed with or secured to the inside of the draw-bar A, and on which is pivoted one end of the knuckle opening lever G, the other end of which indicated at G¹, extends beneath the cam surface B⁴, of the knuckle tail, and is preferably provided with a downwardly extending lug G², to prevent the lug C⁶, of the locking pin from moving too far forward when engaged with the lever.

E, is a cam formed on the side of the draw bar and placed, as shown, in such position as to force the lever G, laterally when it is lifted by the lug on the locking pin. The same lateral movement of the lifting lever is also facilitated by the hook or cam shape of the lug C⁶.

F, is a cam formed on the bottom of the draw bar placed at a range to force the lifting lever laterally back to its normal position of rest when it is disengaged by the lug on the lifting pin.

As shown in Figs. 1, 2 and 3, the pivot D, is formed with a metal projecting lug D', at its end, and the perforation in the lifting lever G, is formed with a corresponding lateral opening G', which permits the lifting lever to be engaged or to be disengaged from the pivot when it is lifted to a practically horizontal position, the lug, however, preventing disengagement of the lever from the pin in any normal position of the assembled coupler. Practically equivalent structures are shown in Figs. 6 and 7. The guard lugs here indicated at D³, and D⁴, in place of being formed on the end of the pivot, consist of lugs extending out from the top of the draw bar, the lever in the construction of Fig. 6, being formed with a transverse slot G⁴, which permits it to clear the guard lug when raised to a practically horizontal position, while in the construction of Fig. 7, a projecting finger G⁵, serves the same purpose. The fit between the pivot D, and the lever G, pivoted

upon it is a loose one both for convenience in manufacture and assembling, and for the further reason that it is advisable to provide for a lateral locking of the lever on the pin as well as for an ordinary turning movement.

In assembling my improved coupler the locking pin is, first of all, inserted in its hole in the head and then the locking lever G, is connected to the pin D, and allowed to drop to its normal non-operative position. The knuckle B, is then inserted in the head, and secured thereto by the usual pin.

The operation of the locking pin on and in direct connection with the knuckle is of the ordinary kind and need not be described.

In lifting the pin to lock set position, that is the position in which the shoulder C⁴, rests on the flange A³, no part of the pin comes in lifting contact with the lifting lever G, but a further upward movement of the pin brings the lug C⁵, into contact with the lower side of the lever G, turning the lever upward on its pivot D, and bringing its end G³, into contact with the cam surface B⁴, after which the further upward movement of the lever by pressing against this surface forces the knuckle tail outward and opens the knuckle, the initial effect of the lifting lever on the knuckle being aided by the construction through which a lateral movement as well as a vertical up and down movement is given to the end of the lifting lever, this lateral movement being imparted by properly placed cams such as the cam E, or the hook like cam of the lug C⁵. The function of the cam F, as heretofore noted, is to return the lifting lever to normal non-operative position when released by the lug on the lifting pin.

It will readily be seen that by properly adjusting the distance between the pivot D,

and the point on the lifting lever G, which is engaged by the lug on the lifting pin, practically any desired leverage can be imparted to the lifting lever, that is to say, the effective end of the lifting end can be made to move with greater or less speed proportionate to the movement of the lifting pin, according as the pin engages the lifting lever nearer to or farther from its point.

Having now described my invention, what I claim as new and desire to secure by Letters Patent is:

1. In a car coupler a knuckle having a cam surface formed on its tail in combination with a lever pivoted at one end in the draw bar in the rear of the locking pin cavity and having its other end extending below the cam on the knuckle tail, a cam arranged to engage the lever as it presses against the cam on the knuckle tail and force it sidewise, a cam placed to engage the lever and return it to normal non-operative position when it is released by the lug on the locking pin, and a locking pin having a lug extending below the lever and in position to come in contact with said lever and press it against the cam when the pin is lifted above lock set position.

2. In a car coupler having a lever adapted to contact with the knuckle tail and open the knuckle, a pivot extending from the inner side of the draw bar over which the lever can be slipped and a guard lug placed to prevent the disengagement of the lever from the pivot in any normal position of the lever in an assembled coupler.

EDWARD O. WARNER.
